PILE FABRIC

Filed May 30, 1944

UNITED STATES PATENT OFFICE

2,381,218

PILE FABRIC

Ezekiel J. Jacob, Brooklyn, N. Y., assignor to Benjamin Liebowitz, New York, N. Y.

Application May 30, 1944, Serial No. 538,017

15 Claims. (Cl. 139—391)

The present application is a continuation in part of my copending United States patent application, Serial No. 424,016, filed on December 22, 1941. This United States patent application 424,016 is a continuation in part of my prior United States patent application 394,895, filed May 23, 1941. This latter application is a continuation in part of my United States patent application 330,504, filed April 19, 1940.

My present invention relates to new pile fabrics.

It is an object of this invention to provide in a heat-resistant pile fabric means adapted to diffuse the heat to which it is exposed throughout the entire fabric thereby diminishing the likelihood of the fabric being destroyed, e. g., by fusing of the glass or similar fibres of which the fabric is made.

A further object of my invention consists in incorporating in a heat-resistant pile fabric means adapted to convey heat from one part of this fabric to another.

Still a further object of my invention consists in providing a heat-protecting non-combustible pile fabric which is also adapted to be used for heating purposes.

Another object of my invention consists of a new non-combustible heat-resistant pile fabric in which heating elements are incorporated in such a manner that any danger of burning by touching of the heated fabric is avoided.

Still another object of my invention consists of a new electrically-heated pile fabric adapted to be used for various purposes, as for instance, for electrical hot pads, heated garments, aviator costumes, heated blankets, heated rugs and other heating means for rooms.

With the above objects in view, my present invention mainly consists of a pile fabric having a fabric base and piles projecting from at least one face thereof, said fabric base made of non-combustible electrically insulating fine filaments and fine metallic wires and said piles of non-combustible electrically insulating fine filaments only.

In accordance with a preferred embodiment of my present invention, I use as non-combustible electrically insulating fine filaments glass filaments and use the fine metallic wires without any covering, i. e., without rubber or textile covering, and obtain in this way a pile fabric of glass filament yarn comprising uncovered metallic wires incorporated in the base of this fabric. Of course, it is also possible to use besides glass other non-combustible electrically insulating filaments as

asbestos and filaments of plastic material fulfilling the same requirements.

I have found that by incorporating fine metallic wires into a pile fabric made of fine heat-resistant electrically insulating glass filaments which simultaneously are also of relatively low heat conductivity, I am able to reduce the tendency of these glass filaments of relatively low heat conductivity to burn out when locally exposed to a temperature appreciably above that which the fabric can otherwise withstand. The reason therefore is that the fine metallic wires incorporated in the heat-resistant glass fabric are of relatively high heat conductivity and distribute the heat over a greater surface, thereby reducing the temperature at the over-exposed region. Thus the heat-resistant electrically insulating glass or similar filaments are protected from being melted or otherwise damaged.

Glass filaments are especially well-adapted for the purpose of this invention: glass is heat-resistant and electrically insulating and can readily be drawn into extremely fine filaments. It is of particular advantage that yarns made of such filaments can be woven or knitted into fabrics. As an example of a specific embodiment, yarns which are very satisfactory for the present purposes may be made by twisting together approximately one hundred glass filaments, each of which has a diameter of the order of magnitude of a few ten-thousandths of an inch; a number, e. g., six of the resulting yarns may be plied or twisted together to form the final yarn of which the desired fabric may be made.

These glass filaments, or the yarns made thereof, form the main part of the new fabric. Incorporated therein are the heat-resistant filaments of relatively high electric conductivity.

I propose to use non-combustible fibres of ductile metals as, for instance, fine metallic wires as such filaments. Suitable metals for these wires are, e. g., nickel, nichrome, chromium-nickel alloys, iron-nickel alloys and other metals having suitable electrical and thermal conductivity and preferably high resistance to oxidation at elevated temperature.

I have found that for certain purposes these metallic wires should preferably have a diameter of about .002 to .005 inch and be properly distributed throughout the heat-resistant electrically insulating filaments for the purpose in view.

In the accompanying diagrammatic drawing I show preferred embodiments of my invention from which the same will be more clearly understood.

In this drawing:

Figure 1 is a cross section of a pile fabric woven in accordance with my present invention;

Figure 2 is a rear view of the pile fabric shown in Figure 1; and

Figure 3 is a rear view of a modified embodiment of the fabric shown in Figures 1 and 2, used as heating fabric.

The pile fabric made according to my present invention and shown in Figures 1 and 2 consists of a fabric base and piles 18. The piles 18 consist of glass or other non-combustible electrically insulating fine filaments or yarn. The fabric base is made by interweaving, interknitting or interlacing glass or other non-combustible electrically insulating fine filaments 18 with fine metallic wires 28 as shown in Figure 1 in cross section. Thus, the piles 18 of the pile fabric conceal the wires 28 which are preferably uncovered, facilitating manufacture of the fabric. The wires 28 are thus spaced from the upper face 28 of the fabric; this fabric face 28 is called the "pile face" of the fabric in the following description and claims.

In Figure 2, I show the pile fabric from the rear. As apparent from this figure, the fine metallic wires are spaced from each other; preferably between each two wires at least one glass yarn is arranged, insulating these wires and preventing short circuits.

The fine metallic wires 28 preferably form spaced fillings of the fabric base as shown in Figure 3; however, I wish to stress that in Figure 2 the fine metallic wires may be either spaced fillings or spaced warp threads of the fabric base.

In any case, it is of importance that the fine metallic wires 28 be spaced from each other. They are, furthermore, in accordance with my present invention, also spaced from the pile face 28 of the fabric by the piles 18 consisting of electrically insulating material as glass or the like.

The fabric shown in Figure 3 is very similar to the one shown in Figures 1 or 2, the only difference is that the parallel fine metallic wire portions are spaced by two fillings of insulating glass threads. The wire 28 is connected at its ends 24 and 25 with circuit 26 which also includes the source of electric current 27. Due to its electric resistance, the wire 28 is heated by the electric current passing through it.

Fabrics of the above described type may be used for various heating purposes as for instance for heating rugs, heating wall coverings, heating pads, heated blankets, and other heating means.

This fabric may also be used for heat insulating purposes as for instance, for fireplace screens and fireplace linings and the like.

It should, however, be stressed that it is also possible to use one and the same fabric for both purposes. Thus, for instance, it is possible to use a fireplace screen consisting of a fabric of the above-described type alternately as heat insulating means in usual manner, or as heating device; in the latter case it is only necessary to connect the ends of the wire or wires incorporated in the fabric of the screen with a source of electric current.

It should be stressed that I have found glass yarn especially adapted for the purposes of the present invention.

The specific embodiments shown and described above are merely illustrative.

What I claim as my invention and desire to secure by Letters Patent of the United States is:

1. A heating fabric having a fabric base and piles projecting from at least one face thereof,

said fabric base consisting of fine metallic electrically conductive wires and fine glass filaments, and said piles consisting of said fine glass filaments only, thus spacing said wires from the pile face of said fabric.

2. A heating fabric having a fabric base and piles projecting from at least one face thereof, said fabric base consisting of interwoven fine metallic electrically conductive wires and fine glass filaments, and said piles consisting of said fine glass filaments only, thus spacing said wires from the pile face of said fabric.

3. A heating fabric having a fabric base and piles projecting from at least one face thereof, said fabric base consisting of non-combustible electrically insulating fine filaments and fine metallic electrically conductive wires, and said piles consisting of non-combustible electrically insulating fine filaments only, thus spacing said wires from the pile face of said fabric.

4. A heating fabric having a fabric base and piles projecting from at least one face thereof, said fabric base consisting of interwoven fine metallic electrically conductive wires and non-combustible electrically insulating fine filaments and said piles consisting of non-combustible electrically insulating fine filaments only, thus spacing said wires from the pile face of said fabric.

5. A woven pile fabric having a fabric base and piles projecting from at least one face thereof, said piles consisting of glass filaments and said fabric base consisting of glass filaments and fine metallic electrically conductive wires incorporated in spaced fillings of the woven base of said pile fabric, spaced from the pile face of said fabric.

6. A pile fabric having a fabric base and piles projecting from at least one face thereof, said piles consisting of glass filaments and said fabric base consisting of glass filaments and fine metallic electrically conductive wires incorporated in the base of said fabric, spaced from the pile face of said pile fabric.

7. A woven pile fabric having a fabric base and piles projecting from at least one face thereof, said piles consisting of glass filaments and said fabric base consisting of glass filaments and fine metallic electrically conductive wires forming spaced fillings of said fabric and being spaced from the pile face of said fabric.

8. A woven heating fabric comprising piles of glass filaments and a fabric base consisting of glass filament yarn woven in consecutive fillings and fine metallic electrically conductive wires incorporated spaced from each other in at least part of said fillings spaced from the pile face of said fabric.

9. A pile fabric having a fabric base and piles projecting from at least one face thereof, said fabric base consisting of fine uncovered electrically conductive metallic wires and fine glass filaments, and said piles consisting of said fine glass filaments only, thus spacing said wires from the pile face of said fabric.

10. A pile fabric having a fabric base and piles projecting from at least one face thereof, said fabric base consisting of interwoven fine uncovered metallic wires and fine glass filaments, and said piles consisting of said fine glass filaments only, thus spacing said wires from the pile face of said fabric.

11. A pile fabric having a fabric base and piles projecting from at least one face thereof, said fabric base consisting of non-combustible electrically insulating fine filaments and fine uncovered electrically conductive metallic wires, and

said piles consisting of non-combustible electrically insulating fine filaments only, thus spacing said wires from the pile face of said fabric.

12. A pile fabric having a fabric base and piles projecting from at least one face thereof, said fabric base consisting of fine uncovered electrically conductive metallic wires and non-combustible electrically insulating fine filaments and said piles consisting of non-combustible electrically insulating fine filaments only, thus spacing said wires from the pile face of said fabric.

13. A woven heating pile fabric having a fabric base and piles projecting from at least one face thereof, said piles consisting of glass filaments and said fabric base consisting of glass filaments and fine uncovered electrically conductive metallic wires incorporated in spaced fillings of said

fabric base of said pile fabric and spaced from the pile face of said fabric.

14. A woven pile fabric having a fabric base and piles projecting from at least one face thereof, said piles consisting of glass filaments and said fabric base consisting of glass filaments and fine uncovered electrically conductive metallic wires forming spaced fillings of said fabric base and being spaced from the pile face of said fabric.

10 15. A woven pile fabric comprising piles of glass filaments and a fabric base consisting of glass filament yarn woven in consecutive fillings and fine uncovered electrically conductive metallic wires incorporated spaced from each other in at least part of said fillings, thus being spaced from the pile face of said fabric.

EZEKIEL J. JACOB.
